Inventor

John C. Skala.

By Clarence A. O'Brien.

Attorney

UNITED STATES PATENT OFFICE.

JOHN C. SKALA, OF NEW YORK, N. Y.

SHADE BRACKET.

Application filed December 15, 1925. Serial No. 75,534.

This invention relates to shade brackets and has for its primary object the provision of such an article particularly adapted for the reception of the flat pintle upon one end of a conventional shade roller, and being so constructed as to prevent the accidental disengagement of this pintle in an upward direction with respect to the bracket and consequently result in the falling of the curtain.

An additional object is to provide means whereby the said flat pintle may be readily forced into engagement with the bracket without requiring the manual manipulation of any mechanism and wherein the said flat pintle may be readily removed from the bracket upon a simple manipulation of a locking member comprising the essential part thereof.

A still further object is to provide a bracket of this character that may be manufactured and marketed in a relatively cheap manner, the same comprising but few parts, and these are so correlated as to substantially nullify any liability of the same becoming out of order.

With the foregoing and other objects in view as the nature of the invention will be better understood, the same comprises the novel form, combination, and arrangement of parts hereinafter more fully described, shown in the accompanying drawing and claimed.

In the drawing wherein like reference characters indicate corresponding parts throughout the several views:

Figure 1 is a front side elevation of my novel shade bracket.

Figure 2 is a rear elevation of the bracket.

Figure 3 is a front elevation thereof, and

Figure 4 is a perspective of a slightly modified form of bracket.

First having reference to Figures 1 to 3 inclusive, my novel shade bracket constitutes the provision of a relatively small and substantially square shaped hollow sheet metal casing 5, that is open at its inner side, and provided at the upper and lower edges at said inner side with laterally extending ears 6-6 provided with openings 7 in order that the same may be readily secured to the inner edges of a window frame when it is desired to mount the shade carried by the roller A, between said side bars of the frame.

The front wall of the casing 5 is formed at its upper end with a vertical slot 8 within

which the flat pintle B upon one end of the roller A is adapted to pass, this slot communicating at its upper end with a cross slot 9 in the top wall of the casing in order to permit of the sliding of said pintle into the slot.

In order that the pintle B will be held in vertical movement within the slot 8 after association with the bracket, I provide an L-shaped arm 10 mounted within the casing 5 directly in back of the front wall thereof, one end of the horizontal portion of the arm being provided with a flat lug 11 that is adapted to project through an opening in the outer side wall of the casing while the other end of said horizontal arm is provided with a pin 12 that extends into an opening in the inner side of said casing as clearly shown in Figures 2 and 3. Surrounding the pin 12 between said inner side wall and the vertical portion of the arm is an expandable coil spring 13 that normally maintains the L-shaped arm in the position shown in Figure 2 in order that the bevel and shouldered end 14 of said vertical portion of the arm will overlie the slot 8, and retain the pintle B beneath the shoulder until said arm is slid rearwardly by pressure upon the lug 11.

In Figure 4 I have disclosed a similar type of bracket, but in this instance the construction of the same is slightly modified in order that the bracket may be disposed upon the outer side of the proper window frame bar. In this instance, the bracket comprises a relatively square flat-like casing 5' open at its inner end and provided with ears 6'-6' similar to the ears 6-6 in the form of the invention shown in Figures 1, 2 and 3. In this instance the inner side wall and top wall of the casing are formed with communicating slots 8' and 9' for receiving the pintle B of the roller A. Within the casing is disposed a latch mechanism similar in all respect to the latch mechanism shown in the form of the invention disclosed in Figures 1, 2 and 3.

It will thus be seen that I have provided a highly novel, simple, and efficient form of shade bracket that will effectively maintain the flat pintle upon one end of a conventional shade roller within the bracket until the same is manually removed therefrom.

Minor changes may be made in the invention without departing from the spirit and scope of the appended claim.

Having thus described the invention, what

I claim as new and desire to secure by Letters Patent is:—

In a shade bracket of the character described, a hollow casing adapted to be secured to a window frame for receiving the flat pintle upon one end of a conventional shade roller, the front wall of the casing being provided with a slot which extends downwardly from the top thereof for permitting the pintle to extend therethrough into the casing, and displaceable means within the casing for securing the pintle within said slot, said means comprising a substantially L-shaped latch member, a hook formed on the upper end of the vertical arm of said L-shaped latch member adapted for engage-

ment with the upper edge of the flat pintle, a pin extending from the inner end of the horizontal arm of the L-shaped latch member, the outer end of said pin being adapted for slidable movement through the adjacent side wall of the casing, a handle portion formed on the forward outer end of the horizontal arm of the L-shaped latch member and extending through the opposite sides of the casing, and a coil spring disposed on said pin between the first mentioned side wall of the casing and the vertical arm of the latch member for normally holding the latch member in engagement with said pintle. 20 25 30

In testimony whereof I affix my signature.
JOHN C. SKALA.
